UNITED STATES PATENT OFFICE.

JOSEPH T. PRICE, OF PHILADELPHIA, PENNSYLVANIA.

VALVE.

Application filed September 22, 1924. Serial No. 739,012.

This invention relates generally to valves, and more particularly to those known as plug valves wherein a rotor is employed to govern flow through them.

5 The purpose of the present improvement is to provide in connection with valves of the type referred to, means whereby the operative or coordinating relation between the fixed and movable ports may be adjusted so 10 that any desired degree of overlap or eclipse may be had between them such as will be effective throughout the extent of valve movement, and whereby the maximum flow through the valves may be predetermined 15 in adapting them to different conditions of use.

How this desideratum may be attained will be readily apparent from the detailed description hereinafter of a typical embodiment 20 of my invention as illustrated by the accompanying drawings whereof Fig. I is a plan view of the improved valve.

Fig. II is a side elevation of the same as viewed from the bottom of Fig. I.

25 Fig. III is a vertical axial section of the valve.

Fig. IV is a diagrammatic view in linear development showing the relation of the fixed and movable flow ports of the valve.

30 Figs. V to IX inclusive show successive positions of the valve from complete closure to full opening.

In the embodiment illustrated, the valve casing designated 10 is cylindric in form and 35 has an outlet 11 projecting laterally from one side thereof. A wall or diaphragm 12 extends across the inner end of the outlet 11, and is provided in the present instance with four discharge orifices 13 preferably 40 arranged in square or diamond formation as shown in Figs. IV to IX. The wall or diaphragm 12 may be made integral with the casing 10, or, if the exigencies of manufacture should require, the same may be provided by employing a tubular insert such as 45 shown at 14 in Fig. III which is made to fit snugly within the cylindric bore of the casing 10 and to rest upon an annular ledge 15 within the latter. The upper end of the 50 casing 10 is closed by a screw cap 16 arranged to clamp the tubular insert 14 against the supporting ledge 15, said screw cap being characterized by an extended circumferential flange 17 useful in the manner to be herein- 55 after explained.

The control member or rotor of the valve designated 18 is made cylindric in conformity with the interior of the tubular insert 14, and is accommodated therein with a snug working fit. The hollow or axial cavity 19 of the control member 18 is in direct communication with the lower open end 20 of the casing 10; and fluid entering the valve leaves the cavity through a multiplicity of lateral and relatively staggered ports 21 in the side wall of said member. These ports 21, it will be observed, are so arranged or grouped as to be registrable in progressively increasing numbers with the discharge orifices 13 as shown in Figs. V to IX inclusive when said control member is moved in the direction of the arrows, respectively in Figs. I and IV, or, in other words, when the diagrammatic lines 1—2—3—4 in the last mentioned illustration are successively made to coincide with a line α on the part 14.

A stem 22, preferably integrally formed with the control member or rotor 18 extends to the exterior of the valve casing 10 to afford attachment for an operating lever or 80 handle 23. This handle 23 is equipped with a depending spring-pressed pin 24 whose lower end is tapered so as to be capable, during operation of the valve, of riding into and out of depressions or apertures 1—2—3—4 in the top face of the circumferential flange 17 on the screw cap 16 of the valve casing 10, and yet to yieldingly maintain the control member 18 in successive shifted positions corresponding to coincidence of 85 the lines 1—2—3—4 with the line α as previously explained in connection with Fig. IV.

In order that the extent of overlap or 90 eclipse between the ports 21 and the discharge orifices 13 may be regulated to modify the range of flow throughout the extent of movement of the control member or rotor 18, as well as to predetermine the maximum flow through the valve, said control member or rotor is made axially shiftable by adjusting means in the form of a sleeve 25 that is independently rotatable on the stem 22 and in screw threaded engagement within an axial opening 26 through the closure cap 100 16 of the valve casing 10. The protruding end of the sleeve 25 has a head 27 which is peripherally knurled or milled as shown in Fig. II to facilitate its ready manipulation; and said sleeve 25 is held against axial 105 110

movement on the stem 22 through abutment of its upper end with the boss of the control handle 23, and contact of its lower end with the shouldered top of the control member or rotor 18. At the region of the contact just referred to, the rotor 18 is formed with an annular recess or groove of V-shaped cross section and the contiguous end of the sleeve 25 is correspondingly accurately configured to engage said groove with a wedge fit, thereby to maintain a fluid tight joint to avoid possibility of leakage from the valve.

Having thus described my invention, I claim:

1. A valve comprising a casing having a discharge of diamond arranged orifices; and a control member rotatable in the casing, said member having staggered ports to govern graduated flow through the valve and capacity for axial adjustment to vary the centric registration of the ports relative to the casing orifices for the purpose of modifying the range of flow through the valve.
2. A valve comprising a casing with diamond arranged discharge orifices in the outlet thereof; and a movable control member

having a series of staggered ports adapted to be brought into registry—in progressively increasing numbers—with the discharge orifices in the casing to govern graduated flow through the valve, said control member having capacity for adjustment in a direction at right angles to its normal movement whereby the centric registration of the ports and orifices aforesaid may be varied to modify the range of flow through the valve.

3. A valve comprising a casing with a discharge of diamond arranged orifices in the outlet; a cylindric plug rotatable in the casing and having staggered ports which afford graduated flow through the valve, said plug having a stem and handle whereby it may be actuated; and a sleeve independently rotatable about the plug stem and in screw threaded engagement with the casing, whereby the plug may be axially moved to vary the centric registration of its ports relative to the casing orifices for the purpose of modifying the range of flow through the valve.

In testimony whereof, I have hereunto signed my name at Philadelphia, Pennsylvania, this 17th day of September 1924.

JOSEPH T. PRICE.
